BY *Drake & Co.*, ATT'YS.

UNITED STATES PATENT OFFICE.

EDWIN R. CAHOONE, OF NEWARK, NEW JERSEY.

HARNESS-MOUNTING.

SPECIFICATION forming part of Letters Patent No. 374,344, dated December 6, 1887.

Application filed August 21, 1886. Serial No. 211,573. (No model.)

To all whom it may concern:

Be it known that I, EDWIN R. CAHOONE, a citizen of the United States, residing at Newark, in the county of Essex and State of New Jersey, have invented certain new and useful Improvements in Harness-Mountings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of harness-mountings, particularly harness-hooks, in which a partial covering-strip of plastic material—such as celluloid or hard rubber—for giving a finish to the body of the mounting is secured to the face of said body by fasteners formed in or on said body. In cases where said strip did not entirely encircle the body metal, but formed terminal ends, said ends were held down by extending the plastic covering material at said ends laterally and downwardly at the opposite sides of said body, so as to form dovetailed or locking flanges, which were held in side recesses in said body, thus locking said ends, without showing on the face of the mounting and thus mar its beauty of finish; but by this construction, while the face of the mounting presented a clean or unbroken surface, the said side flanges of plastic material were apparent when the mounting was viewed in side elevation, and when viewed from this direction said mounting was rendered deficient in beauty of finish by breaking or interrupting the continuity of the bright metallic edge of the body metal at said ends, as will be understood.

It is the especial object of this invention to fasten the said ends of the plastic face covering or strip by providing fasteners thereat which, when the device is viewed in side elevation, will not break or interrupt or mar the face of the said plastic strip when the mounting is viewed edgewise or in plan, and at the same time, when the mounting is viewed in side elevation, will not, as above described, interrupt the apparent continuity of the metallic edge of the body of the mounting, but will allow continuous and parallel edges of the

plastic material and the metal to appear to view to the very extremity of the said plastic strip.

Further objects of the invention are to fasten said partial or face covering to the casting or body of a harness-mounting in such a manner as that the said covering shall be more firmly and securely held in place, the cost of manufacture be reduced, and a more substantial article be obtained.

The invention consists in the process or method of providing harness-mountings with partial coverings and in the improved harness-mounting having the construction and arrangements of parts substantially as will be herein-after set forth, and finally embodied in the clauses of the claim.

Referring to the accompanying drawings, in which like letters indicate corresponding parts in each of the figures, Figure 1 illustrates an unfinished, and Fig. 2 a complete, check-hook which embodies the peculiar features of this invention. Figs. 3 and 4 illustrate certain preferred details of construction.

In said drawings, *b* is a casting or bed-piece, 75 on the outer edge of which are cast, integral therewith, lugs or pins *g*, and at or near the ends or extremities thereof are cast on the face of the casting, or the surface thereof which lies in line with or on the plane with the surface to be covered, in a raised position, binding or clamping lugs *c* and *f*, which, when the covering *d* is pressed in place, are bent down over the edges or ends of said covering, holding the same firmly and securely in place.

The lug *c* is cast so as to form a knob on the end of the hook and give a finish to the same, and serves the purpose of protecting the covering from being torn up in the longitudinal direction of the hook. A web, *e*, is cast at the 90 end of the hook directly under the lug or knot *c*, and serves to strengthen and keep the casting in shape when said lug *c* is bent over upon the covering. It also provides a flat bearing for the hook in hammering down the lug. 95 Said web *e* is dressed off in finishing the hook.

The lugs or pins *g* are cast at or nearly at right angles to the outer surface of the hook, and serve to hold the covering in place and prevent movement in a lateral direction. The 100 said lugs may extend through the covering, and, being polished, serve as ornaments, or

they may be shorter, so as not to show through the covering, but be pressed into the same, so as to secure it to the frame or bed-piece in the manner described. Said lugs may be formed 5 at the edges of the casting in the form of longitudinal ridges, between which the covering is secured to prevent lateral movement. In lieu of projections from the surface of the casting, I prefer, where the covering is to be quite 10 thin, to form one or a series of indentations or depressions, g' , from the side walls of which I prefer to have lugs g to project into the chamber of the depression, as shown in Fig. 4. The covering material being forced into the 15 recesses, whether with lugs or not, is held when the covered surface is convex, and there is no danger of the casting projecting through the thin covering where a plain finish is desired.

The covering d may be of any plastic material which, when pressed under suitable conditions, will close around said lugs or into said 20 depressions and be held in the manner above described.

The curved or convex surface of the casting 25 over which the covering is pressed is, as above intimated, influential in causing the covering to be held in place, as will be evident upon consideration.

In lieu of the depressible lug f , the cover

may be held at the base of the hook or mounting by any other suitable means. 30

Having thus described the invention, what I claim as new is—

1. The process or method of covering harness-mountings, which consists, essentially, in 35 forming a depressible lug on the face or on a plane with the face to be covered, applying a covering material to said surface, and bending said lugs over the end of said covering, substantially as and for the purposes set forth. 40

2. In combination with a metallic harness-mounting body having an end fastening-lug on the face of or in the plane with the surface to be covered, a finishing-strip, d , held at the 45 ends thereof to said body by said fastening-lug, whereby the lateral edges of said mounting at said end present both the edges of the body and those of the covering materials to view and the face of said covering is unbroken, substantially as and for the purposes 50 set forth.

In testimony that I claim the foregoing I have hereunto set my hand this 22d day of July, 1886.

EDWIN R. CAHOONE.
